[57] **CLAIM**

The ornamental design for a multi-unit, individually removable, food dispensing package, as shown and described.

DESCRIPTION

FIG. 1 is a front perspective view of a multi-unit, individually removable, food dispensing package embodying our new design.

FIG. 2 is a front-elevational view on a reduced scale from that of FIG. 1;

FIG. 3 is a rear elevational view thereof;

FIG. 4 is a side elevational view on a scale larger than that of FIGS. 2 and 3 but smaller than that of FIG. 1;

FIG. 5 is a top plan view thereof; and

FIG. 6 is a bottom plan view thereof.

The dash lines in FIGS. 1 and 2 represent score lines.
